UNITED STATES PATENT OFFICE.

GODFREY LOWELL CABOT, OF CAMBRIDGE, MASSACHUSETTS.

APPARATUS FOR MAKING CARBON-BLACK.

1,162,131.

Specification of Letters Patent. Patented Nov. 30, 1915.

Application filed July 16, 1914. Serial No. 851,381.

To all whom it may concern:

Be it known that I, GODFREY L. CABOT, citizen of the United States, residing at Cambridge, in the county of Middlesex and State of Massachusetts, have invented certain new and useful Improvements in Apparatus for Making Carbon-Black; and I do declare the following to be a full, clear, and exact description of the invention, such as will enable others skilled in the art to which it appertains to make and use the same.

This invention relates to apparatus for making high grade carbon-black.

The object of the invention is to provide an apparatus of this character so constructed that there is no appreciable variation of gas pressure within the apparatus and whereby flames of absolute uniformity may be maintained, thus making possible the production of a maximum yield of uniformly excellent carbon-black from a given quantity of gas.

Another object is to provide an improved form of scraping mechanism for removing all carbon-black from the rolls which is so mounted that ease of scraping is obtained and yet the scrapers are so held in contact with the rolls as to efficiently perform their scraping function.

With these and other objects in view, the invention consists of certain novel features of construction, combination and arrangement of parts as will be more fully described and claimed.

In the accompanying drawings: Figure 1 is an end elevation of my improved apparatus, the supply pipe being illustrated in section; Fig. 2 is a side elevation thereof with parts broken off; Fig. 3 is a longitudinal vertical section taken on the line 3-3 of Fig. 1. Fig. 4 is a transverse vertical section taken on line 4-4 of Fig. 3; Fig. 5 is an enlarged longitudinal vertical section through the hood, rolls and scrapers, with parts of the hood broken out; Fig. 6 is a horizontal section through the hood showing the rolls and scraping mechanism in plan, parts being broken off for convenience in illustration. Fig. 7 is an enlarged detail longitudinal section through the riser pipe, screw union, and pressure controlling disk; and Fig. 8 is a detail transverse section through one of the collecting rolls.

In the embodiment illustrated, a suitable structure is shown composed of an angle iron frame 1 mounted on uprights 2.

Mounted in this frame are cylinders or rolls 3, four being here shown, upon which the carbon-black is to be first deposited. These cylinders are tubular and are supported on rotatable shafts 4 driven by gears 5 and worms 6 on a shaft 7 to which latter, motion is imparted by a gear 8.

Disposed within the frame 1 centrally, under each cylinder 3 is a burner or distributing pipe 9 having a series of round hollow burners 10. Each of these pipes 9 is connected with a fuel supply pipe 11 by means of a reducing elbow 12 and a riser pipe 13 in which latter is mounted a screw union 14 having therein an apertured disk 15 which is designed to control the amount of the gas admitted to the burner pipes 9. The supply pipes must be so constructed and be so proportioned to the hole in this disk 15 that there will be no appreciable diminution of gas pressure within the apparatus excepting at this disk, said pipes being sufficiently large to avoid appreciable friction or loss of pressure in passing the gas therethrough, the bores in said disks being of a size to reduce the gas pressure to about one-fiftieth of its original pressure, the burners fed by said disks being of equal size. Thus by the accurate uniformity in these disks, 85 uniform flames can be maintained, thus rendering it possible to obtain a maximum yield of uniformly excellent carbon-black from a given quantity of gas.

Disposed over the cylinders 3 is a removable sheet iron hood 16 provided with a plurality of apertures 17 for controlling the ventilation within the cylinder chamber and which protects the cylinders against drafts.

Arranged below the cylinders 3 and burner pipes 9, is a trough shaped or hopper like member 18 which is designed to shut out the air from the cylinders and to collect the black which is scraped therefrom by means to be described. A screw conveyer 19 is mounted in the bottom of this trough and is designed for removing the carbon-black therefrom to a suitable place of deposit. A pipe 20 extends longitudinally between the cylinders 3 preferably in the alinement with the shafts 4 which support said cylinders, and this pipe is preferably of about one inch and a quarter in diameter but it may be of any other desired size. This pipe 20 is pierced by a plurality of longitudinally spaced apertures 21 which are designed to receive pins 22 for supporting the scrapers

in operative position between the rolls or cylinders 3. As shown, these scrapers comprise blades 23 and 24 fixed to the opposite ends of downwardly curved metal straps 25, 5 two of said straps being here shown connecting each pair of blades. One of these blades is positioned for contact with one of the rolls 3 and the other for contact with the other roll as is clearly shown in Fig. 5. Extending centrally through these straps 25 are the pins 22 which are hung loosely in said straps and are not attached to either the straps or the pipe which provides a slight play and permits easy scraping of the rolls. For the 10 same reason, there is a little play provided between the straps 25 and the steel scraper blades. When the blades are assembled in operative position, the ends of one pair overlap the adjacent ends of the pair in advance 15 thereof and so form continuous scraping blades extending throughout the length of the cylinders. The weight of the blades, straps and pins, is borne by the rolls or cylinders and it is sufficient to cause said 20 blades to closely contact with the rollers and efficiently perform their scraping function. The cylinders 3 on which the carbon-black is deposited, are arranged parallel with the scraping blades 23 and 24 bearing against 25 the periphery of said cylinders so that on the revolution of the cylinders, the carbon is scraped off from the surface thereof and drops into the hopper or trough 18 from 30 which it is conveyed by the screw conveyer 35 19 to some receptacle outside the machine.

It is of course understood that the burning gas below the cylinders deposits the carbon on said cylinders which revolve above them and thus the carbon is efficiently distributed 40 over the surface of said cylinders preparatory to its being scraped therefrom by the blades 23 and 24.

A cover 26 is disposed between each pair

of rolls 3 and as shown is inverted V-shape 45 in cross section with the edges thereof arranged in close proximity to the upper ends of the blades and is designed to prevent any draft between the rolls.

I claim as my invention:

1. A carbon-black apparatus including 50 laterally spaced parallel depositing cylinders, a pipe arranged between said cylinders extending parallel therewith, a plurality of pins loosely mounted in said pipe, straps carried by said pins, and scraping blades 55 mounted on the ends of said straps and positioned to engage the peripheries of said cylinders.

2. A carbon-black apparatus including rev- 60 olubly mounted parallel laterally spaced depositing cylinders, burners arranged below said cylinders, a scraper support ar- 65 ranged between said cylinders, downwardly curved straps loosely mounted on said sup- port midway their ends, and scraping blades 65 loosely mounted at the ends of said straps.

3. A carbon-black apparatus including rev- 70 olubly mounted parallel laterally spaced depositing cylinders, burners arranged below said cylinders, a scraper support ar- 75 ranged between said cylinders, downwardly curved straps loosely mounted on said sup- port midway their ends, and scraping blades 75 loosely mounted at the ends of said straps, said blades being connected in pairs and the pairs arranged in longitudinal alinement with the ends of one strap overlapping the ends of adjacent straps.

In testimony whereof I have hereunto set my hand in presence of two subscribing wit- 80 nesses.

GODFREY LOWELL CABOT.
